UNITED STATES PATENT OFFICE.

JAMES E. STAHL, ELMER S. BENJAMIN, ALBERT B. GRIFFITH, AND ROY LOFFLAND, OF WORTHINGTON, INDIANA, ASSIGNEES TO CEMENT PRODUCTS COMPANY, OF WORTHINGTON, INDIANA, A CORPORATION OF INDIANA.

STAVE-MOLD.

1,325,051.

Specification of Letters Patent.

Patented Dec. 16, 1919.

Application filed April 12, 1917. Serial No. 161,600.

To all whom it may concern:

Be it known that we, JAMES E. STAHL, ELMER S. BENJAMIN, ALBERT B. GRIFFITH, and ROY LOFFLAND, citizens of the United States, residing at Worthington, in the county of Greene and State of Indiana, have invented certain new and useful Improvements in Stave-Molds, of which the following is a specification, reference being had 10 therein to the accompanying drawing.

This invention relates to certain new and useful improvements in molds for forming cement staves used in constructing stave silos as disclosed in our companion application of even date herewith Serial No. 161,599, the object being to provide a mold by means of which a series of staves can be formed, each stave having one longitudinal edge convexed and the opposite edge concaved, the end edges being provided with substantially semi-circular shaped grooves so that when a series of these staves are assembled to produce a structure such as a silo, a series of communicating grooves will be 20 formed which are adapted to be filled with liquid cement for sealing the staves.

Another object of our invention is to provide a mold in which the pallet is in the form of a tray having sides and open ends 30 between which a series of mold strips are arranged so as to form partitions, the end pieces being interlocked with the partitions so as to produce a mold in which the stave can be formed having a semi-circular recess 35 around three of its edges.

Other and further objects and advantages of the invention will be hereinafter set forth and the novel features thereof defined by the appended claim.

40 In the drawings,

Figure 1 is a perspective view of a mold constructed in accordance with our invention showing the same in position upon a jogger;

45 Fig. 2 is a section taken on line 2—2 of Fig. 1;

Fig. 3 is a section taken on line 3—3 of Fig. 1; and

50 Fig. 4 is a detail perspective view of a portion of one of the side and end pieces of the mold.

Like numerals of reference refer to like parts in the several figures of the drawing.

In carrying out our invention we employ

a rectangular open ended tray 1 which is 55 adapted to be arranged on the frame of an ordinary jogger. Arranged within the tray is a series of transversely arranged partitions 3 forming the side pieces of the mold which are preferably substantially semi-circular in cross section having a convexed face 4 and a concaved face 5, the concaved face being provided with a longitudinally disposed rib 6 substantially semi-circular in cross section which terminates short of the 60 ends of the partitions.

The convexed face 4 terminates at shoulders 7 so as to produce a square edge on the concaved face of the stave formed. Arranged between the partitions formed by the 70 side pieces of the mold are end pieces 8 which are curved as shown at 9 at one end adapted to fit within the concaved face of the side piece and are cut away on an arc of a circle at the opposite end as shown at 75 10 in which the convexed face of the abutting side piece is adapted to extend. The end pieces 8 are provided with longitudinally disposed ribs 11 substantially semi-circular in cross section, the end of the rib 80 at the curved end of the side piece being cut away on the arc of a circle as shown at 12, and are adapted to receive the rib 6 of the side pieces so as to form a joint which will produce a stave having a semi-circular 85 groove formed in three of its edges.

The side pieces or partitions of the mold at the end of a tray are held in position by retaining members 13 when a series of molds are arranged within the tray as shown in 90 Fig. 1. A series of staves can be formed at one time, each stave having along one of its side edges a convexed face provided with a longitudinally disposed groove, and along its opposite side edge with a concaved face, 95 the ends of the staves thus formed being provided with longitudinally disposed grooves.

While we have shown a mold constructed to form staves, it is of course, understood 100 that in building a silo it is necessary to form door frames, but as the door frames are constructed in substantially the same manner as staves it can be readily seen that the mold pieces can be utilized for forming the door 105 frames.

We claim:

A mold for forming cement staves com-

- prising an open ended tray, a series of removable partitions arranged transversely within said tray and spaced apart by removable end pieces said partitions being substantially semi-circular in shape in cross section to produce upon one longitudinal edge of the stave a convexed face, and upon the other longitudinal edge a concaved face, the concaved face of said partitions being
- 10 provided with longitudinally disposed ribs substantially semi-circular in cross section and terminating short of the ends thereof, the ends of the end pieces conforming to the shape of the faces of the respective partitions, and having longitudinal ribs substantially semi-circular in shape in cross section
- 15

provided with semi-circular recesses to receive the ribs of the partition, and retaining members arranged at the ends of the tray adapted to engage the partitions for holding said partitions and end pieces in assembled position within said tray. 20

In testimony whereof we hereunto affix our signatures in the presence of two witnesses.

JAMES E. STAHL.
ELMER S. BENJAMIN.
ALBERT B. GRIFFITH.
ROY LOFFLAND.
